UNITED STATES PATENT OFFICE.

LOUIS K. SCOTFORD, OF CHICAGO, ILLINOIS, ASSIGNOR TO THE INDEPENDENT MANUFACTURING COMPANY, OF SAME PLACE.

HAND-STAMP.

SPECIFICATION forming part of Letters Patent No. 634,371, dated October 3, 1899.

Application filed February 27, 1899. Serial No. 707,001. (No model.)

To all whom it may concern:

Be it known that I, LOUIS K. SCOTFORD, of Chicago, in the county of Cook and State of Illinois, have invented certain new and useful Improvements in Hand-Stamps; and I do hereby declare that the following is a full, clear, and exact description thereof, reference being had to the accompanying drawings and to the letters of reference marked thereon, which form a part of this specification.

This invention relates to self-inking hand-stamps of that class provided with a forked handle which has sliding connection with the main part or frame of the stamp and with an oscillating or reversible die-plate pivoted to the arms or forks of the handle and in which said die-plate is moved to carry it against an inking-pad supported in the frame and against the surface to be printed by a relative movement of said handle and frame.

My invention embraces more particularly improvements in the devices for causing the rotation or oscillation of the die-plate; and it consists in the matters hereinafter described, and pointed out in the appended claims.

The invention may be more readily understood by reference to the accompanying drawings, in which—

30 Figure 1 is a view in side elevation of a hand-stamp embodying my invention. Fig. 2 is a central vertical section of the main or lower part of the stamp, taken on line 2 2 of Fig. 1 and showing the die-plate lifted and in contact with the inking-pad. Fig. 3 is a similar sectional view showing the handle depressed and the die-plate in position for printing. Fig. 4 is a detailed plan section taken through one of the end plates of the 35 stamp-frame on line 4 4 of Fig. 2. Fig. 5 is a detail view of the lower end of one of the guide-plates by which rotative motion is given to the die-plate. Fig. 6 is a similar view showing a modified construction in said guide-plate. Fig. 7 is a face view of the lower end of the guide-plate shown in Fig. 6. Fig. 8 is a face view of the lower end of the guide-plate, illustrating a still further modification thereof. Fig. 9 is an edge view of the lower 40 end of the die-plate shown in Fig. 8.

The main part or frame of the hand-stamp

shown in the drawings is made in a familiar manner with vertical end plates or standards A A, each of which is provided with a central vertical slot a, said end plates being rigidly connected with each other by means of a top plate A² and transverse connecting-rods A' A', located near the lower ends of said end plates. The top plate A² is recessed upon its under side to receive an inking-pad A³.

B is the handle, which is provided with parallel arms B' B', which extend outside of the end plates of the frame and are attached at their lower ends to a horizontal rod C, which passes through the slots a a in said end plates and pivotally supports the die-plate D. The top plate A² is provided with a guide-rod A⁴, which enters the handle B, a spring being located between said guide-rod and the handle which operates to retain the handle normally at the upward limit of its movement in a familiar manner.

To the ends of the oscillating die-plate D, at right angles thereto and parallel with the end plates A A, are affixed guide-plates E E, through which the pivot-rod C passes, and each of which is provided at its end adjacent to the die-plate with two cam-slots e e, and at its outer end, or that remote from the die-plate, with two cam-slots e' e'. The cam-slots e e nearest the die-plate are curved inwardly toward each other at their ends, while the cam-slots e' e' are at the same distance apart as the outer ends of said guide-slots e e, or the parts thereof which are most widely separated. The said guide-slots open into a central opening in the guide-plate, as clearly shown in the drawings. The guide-slots of both guide-plates are engaged by two stationary guide-studs F F', fixed in the end plates of the frame and projecting inwardly therefrom. Said guide-studs F F' at each end of the stamp are arranged in the same vertical plane and both at the same side of the central vertical line of the stamp-frame in such manner that when the upper guide-stud F is engaged with one, as e, of the guide-slots the lower guide-stud F' will be engaged with the other, as e', of said slots.

In the operation of the stamp the action of said guide-slots and the guide-studs engaged therewith is as follows: As the pivot-rod C is

depressed the die-plate is carried away from the inking-pad by the movement of the pivot-rod C, and the upper guide-stud F, which is nearest the inking-pad, moves along the guide-slot e and toward the pivotal axis of the die-plate until it reaches the end of the said slot nearest the die-plate, when by the contact of said stud with the outer wall of the slot the guide-plate is held from further downward movement, and the die-plate is thereby caused to rotate about the pivot-rod C as the latter is pushed downward past the said guide-stud F. After the pivot-rod has been carried past the said guide-stud the latter will then move in the guide-slot backwardly away from the die-plate, so that when the pivot-rod C has accomplished half of its downward movement said guide-stud F will stand in the open end of the slot e with which it was first engaged, while the lower guide-stud F' will occupy a similar position in the corresponding guide-slot e at the opposite side of the guide-plate. In the movement of the die-plate and the guide-plate above described the lowermost guide-stud F', which when the die-plate is in contact with the inking-pad maintains a position in the outermost guide-slot e', moves out of said guide-slot e', and as the die-plate is turned and the guide-plate swung laterally moves across the central axis of the die-plate until it reaches a position within the open end of the guide-slot e opposite that engaged by the upper guide-stud F, this being the position which said lower guide-stud occupies when the die-plate reaches its central position or has completed the first half of its downward movement.

In the downward movement of the pivot-rod past the central position above referred to the lower guide-stud F' approaches the end of the slot e nearest the pivot-rod C as the latter passes the said guide-stud and then moves backwardly in the slot until the die-plate is brought into contact with the surface to be printed upon. Said guide-stud F' acts to hold the die-plate horizontal while the impression is being made, as clearly seen in Fig. 3. In the second or lower half of the movement of the handle the upper guide-stud is carried into the guide-slot e', which is at that time at the same side of the guide-plate at which the guide-studs are located, and while the impression is being made said upper guide-stud occupies said slot e' and aids the guide-stud F' in holding the die-plate accurately parallel with the surface to be printed upon at the time of printing.

So far as above described the stamp illustrated is generally similar in construction and operation to other stamps heretofore made.

In the construction of stamps having a frame and a die-plate provided with a guide plate or plates made as described these parts—namely, the main frame and the die-plate, with its guide plate or plates—are constructed separately and afterward assembled by in-

serting the die-plate between the standards of the main frame and then passing the pivot-rod C through the slots of the end plates and through the apertures formed for said pivot-rod in the guide-plates. It is highly desirable for economy of construction that these main parts should be made complete before being assembled—that is to say, that the guide-studs should be inserted in the end plates and the guide plate or plates should be permanently secured to the die-plate before the main parts are assembled—and in order to enable the said guide-studs to be brought into proper engagement with the guide-plates I provide each guide-plate in its outer face with a groove or notch, through which the guide-studs may be passed in inserting the die-plate between the end plates of the frame, said groove or notch being located in the guide-plate elsewhere than in the portions of said guide-grooves e e' which are engaged by the guide-studs at the time of inking or printing or in the turning of the die-plate. Moreover, inasmuch as the guide-plate will commonly be much thinner than the length of the studs I form such groove or notch by bending or offsetting the metal guide-plates in such manner as to give proper form to said notch or groove, while at the same time leaving intact or continuous the marginal parts of the guide-plate, which by reason of the central opening formed therein for the passage of the studs are in effect of ring shape. In the drawings several different ways are illustrated in which the notch or groove referred to may be made.

As illustrated in Figs. 2, 3, 4, and 5, G indicates the notch referred to, which in this instance is located at the outer extremity of the guide-plate E, between the guide-grooves e e', and is formed in a lip or flange E', made integral with the guide-plate and bent at right angles with the same, so as to constitute a rigid connection between the end portions of the guide-plate at opposite sides of said notch, the notch in this instance being formed by cutting a slot in the end portion of the guide-plate, which slot terminates at such distance from the extremity of the projecting part constituting said lip or flange E' that when the latter is bent at right angles to the body of the plate the said notch will extend a sufficient distance inwardly from the outer surface of the plate to give room for the passage of the said guide-studs. Both of the guide-plates being made alike in this respect, it is obvious that the die-plates, with the guide-plate attached, may be easily slipped into place in the frame notwithstanding the presence of the said guide-studs.

As illustrated in Figs. 6 and 7, a notch or groove G' is located in the same position as the notch G before described, and said notch is formed by means of a part E² of the metal forming the end portion of the guide-plate, which part E² is bent or offset inwardly from the plane of the guide-plate by the use of

swaging-dies or in any other suitable manner, so as to form an offset or yoke of such size as to make the notch or groove of sufficient depth for the passage of the guide-studs.

5 The metal constituting the said yoke E² is in this instance necessarily stretched or expanded in the swaging operation to give suitable length to said part. It is not, however, necessary that the notch or groove referred

10 to should be formed in the extremity of the guide-plate, and in Figs. 8 and 9 I have shown a notch G² located in one side of the guide-plate, said notch in the instance illustrated being formed by bending or swaging the metal

15 of the guide-plate, so as to form an offset part or yoke E³.

As a separate and further improvement I have provided a novel construction in the die-plate, as follows: H indicates the printing-die, and I a base on which the said printing-die is mounted or supported. Said die-plate D is made of sheet metal and is provided at its ends with integral extensions, which are bent outwardly from the plane of the plate at one side thereof to form the guide-plates E or similar guide-plates of different form. Said die-plate is also provided at its side margins with holding-flanges d, which are bent outwardly from the side of said plate

20 opposite that at which the guide-plates are located. Said flanges are inclined inwardly at their free edges to give dovetailed form to the recess formed or inclosed by the same. The base to which the die is attached is in-

25 clined at its edges to correspond with the flanges d d, and said base I is adapted to fit between said flanges, so that it will be held thereby in contact with the die-plate. The printing-die H being permanently attached

to the base I constitutes, in fact, one piece 40 with the same, and said parts may be molded of one piece of rubber, or where the said base I is of sponge-rubber or other material different from that of which the die is composed they may be made separately and secured together. The die-plate, made with integral guide-plates at its ends and integral lateral inturned flanges, as described, affords a simple, convenient, and economical construction in said die-plate and a simple means of attaching the printing-die to the die-plate without the use of glue, cement, or other similar attaching means.

I claim as my invention—

1. The combination with a stamp-frame 55 provided with guide-studs, of a die-plate provided with a guide-plate having guide-slots for engagement with said studs, said die-plate having a notch or recess in its outer face for the passage of the said studs in assembling 60 the parts.

2. The combination with a stamp-frame provided with guide-studs, of a die-plate provided with a guide-plate having guide-slots for engagement with the said studs, said guide-plate being provided with a slotted yoke which is bent at an angle to the same and forms a notch for the passage of the said studs in assembling the parts.

In testimony that I claim the foregoing as 70 my invention I affix my signature, in presence of two witnesses, this 18th day of February, A. D. 1899.

LOUIS K. SCOTFORD.
